UNITED STATES PATENT OFFICE.

ULYSSES G. LEEDY, OF INDIANAPOLIS, INDIANA, ASSIGNOR TO LEEDY MANUFACTURING COMPANY, OF INDIANAPOLIS, INDIANA, A CORPORATION OF INDIANA.

DRUM AND TRAP COMBINATION.

Application filed August 5, 1921. Serial No. 490,070.

To all whom it may concern:

Be it known that I, ULYSSES G. LEEDY, a citizen of the United States, residing at Indianapolis, in the county of Marion and State of Indiana, have invented a new and useful Drum and Trap Combination, of which the following is a specification.

The drummer of an orchestra, especially one which provides dance music, is required to manipulate many instruments and appliances in addition to the bass and snare drums and music of this kind is often furnished at points distant from the residence of the drummer.

The object of my present invention is to provide a drum trap combination, the various elements of which shall be of such character that a self contained and easily handled and manipulable outfit can be assembled quickly and also of such character that the bass drum may form a container and carrier for all of the other elements of the outfit, this function being performed without the necessity of interfering in any way with the tensioning and maintenance of the drum heads.

The accompanying drawings illustrate my invention. Fig. 1 is a perspective of the device with its various elements in assembled position, ready for manipulation; Fig. 2, an axial section of the bass drum; Fig. 3, a perspective of the snare drum mounting; Fig. 4 a front elevation of the cradle for the bass drum; Fig. 5, a section through one leg of the cradle; Fig. 6, a vertical section through the instrument table and adjacent portions of the bass drum, Fig. 7, a horizontal section through the cymbal, and its supporting arm; Fig. 8, a detail in partial horizontal section of the mounting for the crash-cymbal; Fig. 9, an elevation of the bass drum with the various implements packed therein, the work table, however, being shown in operative position on the bass drum, and Fig. 10, a perspective view of the device in condition to be readily transported.

In the drawings, 10 and 11 indicate respectively the front and rear heads of the bass drum, said heads being mounted upon independent telescopic cylindrical shell sections, 10' and 11' respectively by the usual counter hoops, the counter hoops, however, being independently associated with their re-

spective shells by any suitable means such as the threaded brackets 12 and the screws 13 which pass through the counter hoops in the brackets. Shell 10' is provided externally with a series of spring fingers 15 secured to the shell. Each finger 15 is projected slightly beyond the adjacent edge of the shell and provided with an inwardly projecting pin 17 which is adapted to enter any one of the suitably arranged series of holes 18 in the shell 11' over which the shell 10' telescopes. Shell 11' may be reinforced by internal hoops 19 in registry with the perforations 18, if desired. Each finger 15 is slotted at 20 and passed through each slot is a stem of a clamping head 21, the stem being rotatably mounted in the shell 10' and the head being adapted to be turned across the perforation 20 so as to hold pin 17 projected into one of the perforations 18, the construction being such that the two shells 10' and 11' may be firmly held in any desired position of axial adjustment.

The counter hoops 22 of the bass drum are preferably L-shaped in cross section, as shown in Figs. 2 and 5, and the bass drum is firmly held in place upon the floor by means of a cradle formed of a stretcher bar 23, two legs 24, 24 having sharpened lower ends and at their upper ends provided with an overlying lip 25 to form a pocket 26 into which the horizontal arm of the hoop 22 may be inverted, as clearly shown in Fig. 5. The stretcher bar 23 is pivotally connected at 27 to one of the legs 24 and at the other end is provided with an open slot 28, formed to receive the stem of a clamping bolt 29 which is passed through the other leg 24 (as clearly shown in Fig. 5), and provided with a butterfly nut 30, the arrangement being such that the slotted end of bar 23 being first detached from the adjacent leg 24, the other leg 24 may be hooked over the counter hoop, the other leg 24 may also be hooked over the counter hoop and the slotted end of bar 23 then slipped over bolt 29 and nut 30 clamped down, thereby providing a light, easily attached and removed cradle by means of which the drum may be firmly supported and held against sliding and rocking movements.

In order that the snare drum may be placed as close as possible to the base drum, thereby facilitating the manipulation of the

other instruments, to which reference will be made, I attach, to the shell 10', a bracket 31 having an out turned ear 31' perforated at 32, and an outwardly projecting lug 33 spaced from ear 31. An arm 34 provided with a laterally offset extension 35 and a snare drum receiving finger 36, set at the proper angle, provides a readily detachable mounting for the snare drum 37. Extension 35 is provided with a perforation 38 adapted to receive the lug 33. Extension 36 is perforated in order to receive a threaded pin 39 carried by a bracket 40 secured to the shell of the snare drum 37, a butterfly nut 41 serving to clamp the snare drum 37 to the arm 34 in such manner that the drum 37 may be swung about a substantially horizontal axis which is formed by the pin 39, and held in any desired position of convenient adjustment by the clamping nut 41.

By raising arm 34 to free the perforation 38 from lug 33, the arm 34 may be withdrawn from bracket 31, and by removing nut 39, the arm 34 may be detached from 25 the snare drum so that the snare drum and arm 34 may be packed into the bass drum in the manner to be described.

The stretcher bar 23 carries a horizontally projected toe 50 upon which may be clamped 30 a drum and cymbal beater 51 of any desired form. The details of this drum and cymbal beater form no part of my present invention and, as there are several such devices on the market and the construction is well known, 35 I do not consider that any further description is necessary.

It is quite common to provide a cymbal 52 connected to the shell of the bass drum in such manner that it may be sounded, either 40 by some instrument in the hand of the drummer or by a beater arm 53, forming part of the device 51. In the present instance, however, I have provided a special mounting for the cymbal by means of which it may be 45 readily adjusted relative to the foot operated beater 53, so that the character of its sounding may be properly varied relative to the sounding of the bass drum.

Secured by any suitable means to shell 10' 50 is an arm 60 (Fig. 7) provided with an out turned finger 61 which has an open ended slot 62 formed therein. This slot 62 is formed to receive the shank of a threaded bolt 63, the threaded end of which is projected through the central perforation of the cymbal 52 and carries a clamping butterfly nut 64. Interposed between cymbal 52 and finger 61 is a tapered washer 65 upon the tapered or inclined face of which the cymbal 55 is clamped, the arrangement being such that by rotating this washer upon the shank 63, and relative to arm 61, the distance of the cymbal from the normal point of action of the beater 53 may be readily adjusted. By 60 reason of the slotted construction of finger

61, a slight loosening of nut 64 permits withdrawal of the cymbal from the drum shell 10' so that the connection between arm 60 and the shell 10' may be a permanent one.

In an equipment of the sort under discussion, it is quite important that various accessories, such for instance as the musical block 70, the cow bell 71, the crash cymbal 72, etc., through a very considerable range of instruments and implements, musical, noisy, and otherwise, be arranged within easy access of the drummer. For this purpose, I have provided what I call an instrument support table which may be readily attached to and detached from the bass drum. This table comprises a main board or plate 73 of sufficient width to bridge the space between and lie upon the counter hoops 22 of the two bass drum sections 10 and 11, and of sufficient length to provide ample space for the various implements and instruments which the drummer may desire to attach. Secured to the under face of table 73, preferably by brackets 74 which will preferably form a pivotal mounting, are two tie strips 75, 75, preferably formed of thin metal and each provided at its lower end with a bend or pocket 76, the construction being such that the pockets 76 may be slipped over adjacent bracket 12 and the tie strips then held in place by screwing the clamping screws 77 down upon or under the turn of the bracket. The tie strips 75 are so proportioned in length that when they are in position as shown in Fig. 6, the table 73 will be very slightly tensioned upon the counter hoops 22.

The pivotal connection between the tie strips 75 and the table 73 permits these tie strips to be folded down upon the table so that it may be readily stored inside of the bass drum sections for transportation. Each implement 70, 71, etc., will be provided with a holding clamp having a portion 80 adapted to be slipped over the edge of the table and held in place by a clamping screw 81 which may conveniently engage the under face of the table. The head of bolt 82 engages under the adjacent flange of ring 22 and thus holds the rear edge of the table down.

In order that the crash cymbal 72 may be held at a convenient point, the table 73 carries a bolt 82 which is projected upwardly from the upper face of the table and provided with a butterfly nut 83 beneath which may be slipped the slotted foot 84 of a standard 85. Standard 85 carries an adjustable clamping piece 86 which has an intermediate cylindrical pocket 87, receiving the standard 85 and spring ends 88 and 89 through which a clamping screw 90 is passed. The spring end 89 is provided at its end with a horizontally extended notched finger 91 adapted to receive the rod 92 which is extended through the perfo-

ration 93 in the head 94 of bolt 90, the arrangement being such that a tightening of nut 95, on bolt 90 will not only clamp the element 86 on the standard 85 but will also 5 clamp rod 92 into the notch of finger 91 and upon the element 86.

Rod 92 carries a hook 97 at its outer end to form a support for the crash cymbal 72. By loosening nut 95 the height and lateral 10 position, both sidewise and backward and forward, of the crash cymbal 72 may be quickly adjusted so as to bring the crash cymbal into exactly the right position for the most convenient manipulation. The 15 loosening of nut 95 also permits rod 92 to be slipped out of the notch finger 91, and rod 92 to be then swung down parallel with standard 85 so that this element may also be readily packed in the shell of the bass 20 drum.

As illustrated in Fig. 9, all of the various implements and instruments, after having been detached from the shell of the bass drum, may be packed in the said drum, the 25 two sections 10 and 11 being separated from each other for that purpose and then reassembled. In order that the skins of the bass drum may not be injured by the storage of the various devices within the shell, suitable 30 disks 11^a of hard fiber may be provided. When all of the implements and instruments have been packed within the bass drum, it may be placed within a suitable telescopic carrying case such as is shown in 35 Fig. 10.

I am aware that it has heretofore been proposed to form a shell of a bass drum with an opening covered by a trap door in order that elements or attachments might 40 be packed within the drum for transportation, but the size of the opening in such a construction is necessarily quite limited, not only because the shell of the drum may not be materially weakened, but also because it 45 is customary to extend the head tensioning members from one counter hoop to the other and, of course, a trap opening is limited as to size to the distance between two adjacent tensioning devices. By making the two sections 50 of the bass drum telescopic and absolutely independent of each other so far as the head tensioning construction is concerned, it becomes possible, by separating one shell of the drum from the other, to 55 make available the entire diameter of the

bass drum for the insertion of the various elements which are to be packed therein.

So far as I am aware, it is only by such a construction that an instrument as large as a snare drum could possibly be packed 60 inside of the bass drum.

I claim as my invention:

1. A bass drum comprising telescopic shells separable from one another to expose the interior of each shell throughout 65 its entire diameter, each carrying a drum head and independent tensioning means, and separable means for holding said telescopic sections in drum forming relationship with each other. 70

2. The combination with a base drum formed by two telescopic shells separable from one another to expose the interior of each shell throughout its entire diameter, each shell carrying an independently tensioned drum head, of a plurality of musical instruments including a snare drum, each having means by which it may be detachably attached to one of the bass drum shells, the several instruments being receivable 80 within the base drum shells. 75

3. The combination with a base drum formed by two telescopic shells separable from one another to expose the interior of each shell throughout its entire diameter, each shell carrying an independently tensioned drum head, of a plurality of musical instruments each having means by which it may be detachably attached to one of the base drum shells, the several instruments being 85 receivable within the base drum shells. 90

4. A base drum comprising two shells, each carrying a drum head and independent head tensioning means, said shells being detachable from one another and separable 95 means for holding said shells together in drum forming relationship with each other.

5. A base drum comprising two separate shells, each carrying a drum head and independent head tensioning means, one of 100 said shells having means for telescopically positioning the other shell with respect thereto, and separable means for holding said telescopic sections in drum forming relationship with each other. 105

In witness whereof I, ULYSSES G. LEEDY, have hereunto set my hand at Indianapolis, Indiana.

ULYSSES G. LEEDY.
